UNITED STATES PATENT OFFICE.

EDWARD C. BENGEL, OF ST. LOUIS, MISSOURI, ASSIGNOR TO THE LAMSON COMPANY, OF SYRACUSE, NEW YORK, A CORPORATION OF MASSACHUSETTS.

PNEUMATIC DISPATCH CARRIER.

Application filed September 9, 1926. Serial No. 134,398.

This invention relates to carriers for pneumatic dispatch systems and more particularly to carriers of the so-called take-apart type, such as disclosed in the patent 5 to James G. Maclaren No. 1,553,869, September 15, 1925. Carriers of this type comprise inner and outer telescoping shells, each shell having a fixed head at one end. Access to the interior is ordinarily obtained by 10 rotating the shells relatively to one another whereby to bring the openings in the respective shells into registry, but for certain reasons, for example, to position or remove index slips disposed between the meeting 15 surface of the shells, it is desirable at times to separate the shells by relative axial movement. However, this axial movement is usually undesirable and to prevent accidental separation during transmission or handling 20 of the carrier, a stop pin is provided on one shell which engages an abutment element on the other.

In the carrier disclosed in the above patent the abutment is provided at one point 25 with a passage through which the stop pin may be moved to permit separation of the shells when desired and although the stop pin and abutment ordinarily and for most 30 purposes avoid the danger of accidental separation of the shells, the provision of the aforesaid channel makes such accidental separation at least theoretically possible and for this reason users of pneumatic dispatch carriers sometimes object to this type of carrier.

In accordance with the present invention I provide a safety device applicable to carriers of the above type and which positively prevents accidental separation of the shells 40 although permitting intentional separation when desired.

In the accompanying drawings Fig. 1 is a side elevation of a take-apart carrier of the type referred to, showing the inner and outer shells relatively positioned to give access to the interior;

Fig. 2 is a side elevation of the same carrier, but with the shells separated and axially aligned to show details of construction 50 of the inner shell;

Fig. 3 is a fragmentary radial section to large scale showing the shells assembled and the safety device in place;

Fig. 4 is a fragmentary section substantially on the line 4-4 of Fig. 3; and

Fig. 5 is a section similar to Fig. 3 but illustrating a modified form of the safety device.

Referring to the drawings the numeral 1 designates the inner cylindrical shell of 60 the carrier, such shell being provided with a head 2 at its outer end. In this type of carrier the head is usually permanently attached to the shell, for example, by means of rivets, not shown.

The outer shell 3 is also provided at its outer end with a non-removable head 4, and is furnished with the usual driving washer 5 adapted to make air-tight contact with the inner surface of the pneumatic transmission 70 tube.

The inner shell 1 is furnished with an elongate access opening 6 in its wall, such opening being adapted to register with a corresponding access opening 7 in the wall 75 of the outer shell 3 when the shells are turned to the proper relative position as shown in Fig. 1.

The inner end of the access opening 6 in the shell is defined by an axially narrow portion 1^a of the shell hereinafter referred to as the "abutment member". This abutment member is furnished with a shallow, axially extending channel 8, as described in the aforesaid patent, such channel extending 80 from the edge 10 of the abutment member 1^a to the inner end of 10^a of the shell. This channel may conveniently be formed by pressing the metal of the shell inwardly during the process of manufacture. While the 85 channel is here shown as substantially straight and parallel to the axis of the shell, it is contemplated that the channel might be of zig-zag or curved form, or oblique to the axis if desired.

The channel 8 forms a passage for the head 9 of a stop pin projecting inwardly from the wall of the outer shell 3. This stop pin may conveniently consist of a rivet inserted at this point, the inner head 9 of 100 the rivet preferably being flattened to permit it to pass readily through the channel 8.

When the parts are assembled the head 9 of this pin normally engages the edge 10 of the abutment member 1^a and thus prevents 105 relatively axial movement of the shells. However when the shells are turned to one predetermined relative position, wherein the pin 9 is opposite the end of the channel 8, the shells may be separated by relatively 110

axial movement, all as described in the aforesaid patent. To prevent such separation accidentally the safety device herein-after described is provided.

- 5 This safety device as shown in Figs. 3 and 4 consists of a strip of sheet material, preferably somewhat resilient metal, bent substantially into U-form and comprising the legs 13 and 14. The leg 13 is adapted to 10 be slipped endwise into the recess or channel 8 between the surfaces of the shells. The interposition of this clip between the head 9 of the stop pin and the edge of the abutment 1^a prevents the pin from entering 15 the channel and thus prevents accidental separation of the shells. The other leg 14 of the clip is disposed at the inner surface of the abutment 1^a and provides a convenient handle for manipulation of the clip in inserting or withdrawing the latter.

While the resiliency of the clip may be relied upon to retain it in position, particularly if the inner leg 13 be deflected slightly from a straight line as shown, it is preferred 20 to provide more certain retaining means. For example, by depressing the metal of the abutment 1^a at a point intermediate the ends of the channel 8 I provide a recess 16 adapted to receive a projection or boss 17 25 on the leg 13. When the clip is slipped into place the metal of the abutment 1^a springs sufficiently to permit the boss 17 to pass the narrow part of the channel and to snap into the recess 16. The clip is thus retained in 30 assembled relation until withdrawn by the application of considerable force to the handle portion 14.

In Fig. 5 a modified form of clip is disclosed, such clip 18 consisting of a substantially straight piece of metal having the boss 19 adapted to snap into the recess 16 of the abutment. When this type of clip is once inserted it is more difficult to remove since 40 it is not provided with a handle and may thus be employed if it is desired to connect the shells so as permanently to eliminate the take-apart character of the carrier.

By the employment of the clip shown in Figs. 3 and 4, it is possible positively to 50 prevent accidental separation of the shells, regardless of their relative position of rotation, although if it be desired at any time to separate the shells the clip may readily be withdrawn and the shells relatively rotated 55 to bring the stop pin into registry with the channel 8.

While certain desirable forms of safety device have herein been disclosed it is to be understood that in its broader aspects the 60 invention is not limited to this particular embodiment but that other and equivalent arrangements may be substituted therefor as circumstances may demand.

I claim:

- 65 1. A pneumatic dispatch carrier of take-

apart type having relatively rotatable telescoping shells, said shells being separable by relative axial movement when relatively rotated to a predetermined position, and a resilient clip adapted to be interposed between elements of the respective shells to prevent relative axial movement of the shells when in said predetermined position.

2. A pneumatic dispatch carrier comprising telescoping shells, a stop member projecting from one shell, an abutment element on the other shell, said abutment having a channel through which the stop member may pass to permit axial separation of the shells, and means for obstructing said channel.

3. A pneumatic dispatch carrier of take-apart type having telescoping shells, said shells being separable by relative axial movement, and a removable stop adapted to be seated in a recess in one shell and by its interposition between elements of the respective shells to prevent relative axial movement of the shells.

4. A pneumatic dispatch carrier of take-apart type having telescoping shells, said shells being separable by relative axial movement, one of the shells having a depression in its wall providing an elongate recess between it and the wall of the other shell, and a clip adapted to be slid into said recess and when seated therein to prevent relative axial movement of the shells.

5. A pneumatic dispatch carrier comprising relatively rotatable telescoping shells, a rigid stop lug projecting from one shell and normally engaging a part of the second shell to prevent relative axial movement of the shells, the part with which the stop lug engages having an axially extending channel through which the stop lug may pass when the shells occupy one predetermined relative position, and means for closing said channel.

6. A pneumatic dispatch carrier having telescoping shells, the inner end of one shell having an axially narrow circumferentially extending abutment member provided with a channel extending from one edge to the other, a projection upon the inner portion of the other shell normally engaging the abutment member but capable of movement through said channel to permit axial separation of the shells, and a removable clip for obstructing said channel, said clip and the abutment member having cooperating elements for retaining the clip in operative position in the channel.

7. A pneumatic dispatch carrier of take-apart type having telescoping shells, said shells being separable by relative axial movement, and a U-shaped retaining clip of sheet material, one leg of said clip being adapted to be interposed between elements of the respective shells and the other leg of the clip constituting a handle for manipulating it.

8. A pneumatic dispatch carrier comprising telescoping shells, a stop member projecting from one shell engaging an abutment element of the other shell normally to prevent relative axial movement of the shells, said abutment having a way therethrough adapted to permit the passage of the stop and the axial separation of the shells, and means for obstructing said way comprising a clip having a portion fitting within the channel and a handle portion projecting beyond the channel and constituting means for removing the clip.
9. A pneumatic dispatch carrier having telescoping shells each having an access opening in its peripheral wall, the inner end of the access opening of one shell being defined by the edge of a circumferentially extending abutment member, the abutment member having a channel extending from the access opening to the inner end of the shell, a projection carried by the other shell normally engaging the edge of the abutment

but capable of moving through the channel to permit axial separation of the shells, and a removable clip for obstructing the channel, said clip having a boss engageable with a recess in the wall of the channel to prevent accidental removal of the clip.

10. A pneumatic dispatch carrier comprising telescoping shells, a stop member projecting from one shell, the other shell having an abutment with which said stop member normally engages, said abutment having a passage through which the stop member may be moved to permit axial separation of the shells, and a substantially U-shaped clip, one leg of which may be seated in the passage in the abutment to prevent movement of the stop member along said passage, the other leg of the clip being exposed and constituting means for removing the clip from operative position.

Signed by me at St. Louis, Missouri, this 28th day of August, 1926.

EDWARD C. BENGEL.
